UNITED STATES PATENT OFFICE.

WILLIAM C. MEYER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FEED MECHANISM FOR SHOE-SEWING MACHINES.

1,298,759.

Specification of Letters Patent.

Patented Apr. 1, 1919.

Original application filed July 29, 1913, Serial No. 781,785. Divided and this application filed February 28, 1916. Serial No. 80,909.

To all whom it may concern:

Be it known that I, WILLIAM C. MEYER, a citizen of the United States, residing at Beverly, in the county of Essex and Commonwealth of Massachusetts, have invented certain new and useful Improvements in Feed Mechanism for Shoe-Sewing Machines; and I do hereby declare the following to be a full, clear, and exact description of the invention, such as will enable others skilled in the art to which it appertains to make and use the same.

The present invention relates to shoe sewing machines and more particularly to sole-sewing machines of the type provided with a straight hook needle and a rotatable work support or horn arranged to extend within the shoe, such machines being generally known in the art as machines of the McKay type.

Machines of the McKay type are ordinarily provided with a feed point or awl which, during each cycle of operations, is projected into engagement with the work, and is then advanced in the direction of the seam to feed the work. The feed point is usually supported and actuated in such a manner that during its advancing or work feeding movement it is swung about a horizontal axis, thereby varying the direction and extent of engagement of the feed point with the work, which has resulted in uncertainty in the feeding action of the feed point.

One of the objects of the present invention is to provide shoe sewing machines of the McKay type with mechanism of simple construction for supporting and actuating the feed point in such a manner as to feed the work with greater accuracy and certainty than the feeding devices of such machines heretofore constructed. With this object in view, the invention contemplates the provision, in combination with mechanism for reciprocating the feed point laterally in the line of feed, and means operated by the lateral movement of the feed point, for moving the feed point into engagement with and for retracting it from the work, of supporting and controlling means for the feed point, constructed to maintain the angular position thereof unvaried during the advancing movement of the feed point to feed the work.

After the seam has been completed, the machine should be brought to rest at a point 55 in the cycle of operations in which the needle is at or near its highest position, and the presser foot is free to be lifted to permit the removal of the work and the insertion of another piece of work in operating position 60 in the machine. Before removing the work the operator severs the side or leg of the needle loop leading to the work. At this point in a cycle of operations, the feed point is in a position adjacent the needle, and 65 therefore interferes with the severing of the thread of the needle loop.

A further object of the invention is to produce a machine of the McKay type in which the parts of the machine, upon stopping the machine, may be brought to such positions that they do not interfere with the severing of the thread of the needle loop, and that they form no obstruction to the removal and insertion of the work. With this 70 object in view, a feature of the invention contemplates the provision of means for withdrawing the feed point from its normal position in the direction away from the needle upon stopping the machine. Broadly 75 considered, the invention contemplates any suitable means for accomplishing this result. In the preferred form of the invention, however, the machine is provided with means for disconnecting the feed point from its actuating mechanism upon stopping the machine, and with means for withdrawing the feed point away from the needle when it has been thus disconnected. In the best form 80 of the invention which has been devised, the 85 machine comprises an automatic stop mechanism for bringing the machine to rest at a definite point in a cycle of operations, and is provided with means operated by the engagement of the stopping devices which 90 finally bring the shaft to rest for automatically disconnecting the feed point from its actuating mechanism.

Further features of the invention consist of certain novel and improved constructions, 100 arrangements and combinations of parts hereinafter described and defined in the claims, the advantages of which will be obvious to those skilled in the art from the following description.

The present application constitutes a di-

vision of an application Serial No. 781,785, filed July 29, 1913, on which Patent No. 1,177,581, dated March 28, 1916, has been granted.

- 5 The features of the invention will be readily understood from an inspection of the accompanying drawings taken in connection with the following detailed description of the constructions therein shown.
- 10 In the drawings illustrating a machine embodying the invention in its preferred form, Figure 1 is a view in side elevation of the complete machine; Fig. 2 is a view in front elevation, partly in section, of the head 15 of the machine; Fig. 3 is a plan view partly in section, illustrating all except the rear portion of the head of the machine; Fig. 4 is a detail view in vertical section illustrating the feed mechanism and certain associated parts; Fig. 5 is a detail sectional view 20 taken substantially on the line 5—5 of Fig. 4; Fig. 6 is a sectional view taken substantially on the line 6—6 of Fig. 3; Fig. 7 is a view in side elevation, partly in section, of 25 the mechanism illustrated in Fig. 6 looking from the left; Fig. 8 is a detail sectional view taken substantially on the line 8—8 of Fig. 7; Fig. 9 is a sectional view taken substantially on the line 9—9 of Fig. 8; and 30 Fig. 10 is a detail view in side elevation partly in section, illustrating particularly the mechanism by which the feed point is connected with its actuating mechanism.

The machine illustrated in the drawings 35 comprises the usual vertically reciprocating straight hook needle indicated at 10 which, during each cycle of operations, is projected through the work into position to receive the thread from a looping device located in 40 the tip of the horn. The cast-off for preventing the previously formed loop from catching in the hook of the needle as the needle is retracted from the work, is indicated at 12. The work is engaged during 45 the sewing operation between the upper surface of the tip of the horn and presser foot 14 which is arranged for vertical movement to accommodate work of varying thicknesses. These parts, their actuating mechanisms and mode of operation, and the arrangement and operation of other parts 50 shown in the drawings and mentioned briefly in connection with the description of the present invention, are fully described in 55 said application, Serial No. 781,785.

The work is fed at intervals during the operation of the machine by the feed point 16 which is projected into the work and is then advanced in the direction of the seam 60 to feed the work. The feed point 16 is mounted upon a slide 18 arranged in an opening in the lower end of the presser bar 20. The lower face of the forwardly extending portion of the slide 18, in which the feed 65 point is secured, is inclined and engages the

adjacent inclined faces of the presser bar and presser foot, as clearly shown in Figs. 2 and 4, as the feed point is projected into engagement with and retracted from the work. The slide 18 is U-shaped in section, 70 as shown in Fig. 5, and its sides embrace the lower end of an L-shaped slide 24, the vertical arm of which slide is arranged in a groove in the presser bar and is held in place in said bar by the adjacent portion of the frame through which the presser bar slides. A horizontal slot 26 is formed in the slide 24, and cam slots 28 are formed in the portions of the presser bar which embrace the slide 18 and the slide 24. The 75 slide 18 and the slide 24 are connected with each other and with the presser bar by means of a bolt or pin 30 fixed in the slide 18, which engages in the slot 26 in the slide 24 and in the cam slots 28 in the presser bar. 80 The feed point is actuated through an oscillatory arm 32 connected with the bolt 30 by means of a link 34. Each of the slots 28 is constructed so that the forward or right-hand portion thereof is inclined at a considerable angle to the horizontal or to the surface of the work, and so that the left-hand portion thereof is very nearly horizontal but inclined downwardly slightly in the direction of the feed movement of the work. 85 During the forward movement of the feed point, the angular position of the feed point is maintained substantially unvaried by the engagement of the surface 36 of the slide 18 with the lower horizontal surface of the slide 24, said surfaces being held in engagement during the advancing movement of the slide 18 by a tension spring 38 connecting the rear end of the slide 18 with the end of the arm 32. Starting with the feed point in 90 retracted position out of engagement with the work, as shown in the drawings, when the slide 18 is carried to the left by the lateral swinging movement of the arm 32, the feed point is first moved downwardly at an angle by the movement of the bolt 30 through the sharply inclined portions of the cam slots 28, and is thus projected into engagement with the work. While the bolt 30 is moving through the left-hand or slightly 95 inclined portions of the slots 28, the feed point acts to feed the work, and on account of the slight inclination of said slots, the feed point is projected slightly farther into engagement with the work as it advances, 100 which insures certainty and reliability in the feeding action. During the entire movement of the feed point from retracted position out of engagement with the work, to its limiting position in the direction of feed, it is maintained in unvaried angular position by the engagement of the slides 18 and 24, the slide 24 moving vertically in its guides during the advance of the feed point. 105 On account of the structure of the cam slots 110

28 as described, the slide 18 is not lifted away from the work during the retracting movement of the feed point until the bolt 30 reaches the sharply inclined portions of the 5 cam slots, which occurs near the end of the retracting stroke of the feed point. In order to permit the feed point to be drawn back without undue resistance, the connection between the slides is arranged to permit the 10 slide 18, as it is retracted, to swing about the connecting bolt 30. To this end, the slide 18 is cut away at 40 at an angle to the adjacent horizontal face of the slide 24. As the slide 18 is drawn back after the feeding 15 movement of the feed point by the backward pull of the link 34 on the bolt 30, the resistance of the work against the feed point will cause the slide 18 to swing about the bolt 30 against the tension of the spring 38. 20 The feed point will drag back over the surface of the work until the bolt reaches the sharply inclined portions of the cam slots 28, when the slides will be lifted to bring the feed point out of engagement with the 25 work and restore the parts to the positions shown in Figs. 1 and 3.

During the sewing operation, the machine is driven by means of a belt 42 passing about a pulley 44 fast on the main shaft 46 of 30 the machine, and connecting said pulley with a pulley 48 mounted upon a driving shaft 50 located in the base of the machine. The shaft 50 is provided with a loose pulley 52 and with a pulley 54 splined 35 thereto but movable longitudinally thereof, which is driven by a belt from a power shaft. The pulley 48 is loosely mounted on the shaft 50 in front of the pulley 54, and is provided with a ring of friction material 40 for engagement with the adjacent surface of the pulley 54. A fourth pulley 56 is pinned to the shaft 50, and the pulley 48 carries a second ring of friction material for engagement with the adjacent surface 45 of the pulley 56. The shaft 50 is arranged for longitudinal movement in its bearings, and when said shaft is thrust endwise toward the rear of the machine, the pulley 48 is clutched between the opposed faces of 50 pulley 56 and pulley 54 and thereby caused to rotate with said pulleys. When the shaft is released and allowed to move forwardly or toward the front of the machine, the loose pulley 48 is carried out of clutching engagement with the pulleys 54 and 56. The 55 shaft 50 is actuated to clutch the pulley 48 between pulleys 54 and 56 by suitable connections from the treadle 60. Said connections comprise a bell crank lever pivoted 60 on a stud 62 and provided with an arm 64 which engages the end of the shaft 50. The other arm 66 of the bell crank lever is provided with a forked forward extremity which embraces a rod 68, which is the rod 65 which controls the device for throwing the stop mechanism into operation. The rod 68 is connected at its lower end with a lever 70, which lever is arranged to be actuated from the treadle. A collar 72 is secured to the rod 68 above the arm 66, and the rod 70 68 is yieldingly held in raised position by the coiled spring 74. The treadle 60 is pivoted on a horizontal stud 76 carried by a block mounted on a vertical swivel pin 78. This manner of mounting the treadle 75 permits the treadle to be swung vertically and horizontally. The rearwardly extending arm 80 of the treadle is provided with a lateral projection 82 which is adapted to engage beneath the forward end of the lever 80 70. When the projection 82 is beneath the arm of the lever 70, and the treadle is depressed, the rod 68 is moved downwardly and actuates the bell crank 66 to thrust the shaft 50 rearwardly and thereby clutch the 85 pulley 48 to the shaft and start the machine into operation. When the forward end of the treadle is released, it is lifted by a coiled spring 84, allowing the rod 68 to be lifted by the spring 74 to release the lever 64—66. 90 The shaft 50 may then move forward to release the pulley 48 from clutching engagement with pulleys 54 and 56.

In order to permit the work to be removed when the seam has been completed, 95 and another piece of work to be introduced easily and quickly, the machine is provided with mechanism for automatically arresting the rotation of the shaft at the point in the cycle of operations when the needle is retracted out of engagement with the work and the presser foot is free to be lifted. When the treadle is released at the end of the sewing operation, the mechanism which 100 brings the machine to rest with the parts in proper positions for the removal of the shoe is thrown into operation. This mechanism comprises a friction clutch, one member of which is driven at slow speed in a forward direction, and which, when the clutch members are engaged, first acts as a brake to slow the shaft down to the slow speed of the forwardly driven member, and then to drive the shaft at slow speed in a forward direction to bring the devices which 105 finally arrest the rotation of the shaft into engagement. The friction clutch consists of clutch members 86 and 88, of which the member 86 is loosely mounted on the main shaft 46 of the machine, and is driven at 110 slow speed in the same direction as the normal direction of rotation of the shaft 46, by means of a spiral pinion 90, mounted on a hollow shaft or sleeve 92 journaled in bearings 94 in the machine frame, which meshes 115 with the teeth of a spiral gear 96 secured to or formed integral with the clutch member 86. The hollow shaft 92 is constantly driven during the rotation of the main shaft of the machine through a friction 120 member 125

130

clutch connecting said shaft with a pulley 98 which is continuously driven by means of a belt 100 connecting said pulley with the pulley 56 mounted on the shaft at the base 5 of the machine. The clutch connection between the shaft 92 and the pulley 98 consists of a clutch member 102 secured to or formed integral with the shaft 92, and a second clutch member 104 carried by the pulley 98. 10 The pulley 98 is journaled upon a rod or shaft 106 extending through the hollow shaft 92, and is confined between collars carried by the rod, as clearly shown in Fig. 8. The clutch members 102 and 104 are engaged and disengaged by the longitudinal 15 movement of the rod 106 within the hollow shaft 92, as will be presently explained. A brake is provided to arrest the rotation of the shaft 92 and the pinion 90 when the 20 clutch connecting said shaft with the pulley 98 is disengaged. This brake comprises a friction brake member 108 mounted on the shaft 92 to rotate with said shaft. The brake member 108 is connected with the 25 hollow shaft by a pair of blocks or keys 110 secured by screws to the member 108 and arranged to project inwardly through slots 112 in the adjacent portion of the hollow shaft. The brake member 108 is arranged 30 to be engaged with the interior of a brake shoe 114 formed on the frame of the machine when the rod 106 is moved in a direction to disengage the clutch. The inner ends of the blocks 110 extend inwardly to points 35 adjacent to the reduced portion 114 of the rod 106, and the brake member 108 is normally held in position on the rod with the blocks 110 in engagement with the shoulder 116 by a coiled spring 118 sur- 40 rounding the reduced portion of the rod 106, and engaging the member 108 outside of the hollow shaft 92, said spring being confined between the member 108 and a collar or washer 120 held by a nut threaded on the 45 end of the rod. The members of the friction clutch are held normally in engagement by means of a second coiled spring 122 surrounding the reduced portion 114 of the rod, and arranged within the coiled spring 118. 50 The coiled spring 122 engages at its inner end the projecting extremity of the hollow shaft 92, and acts to maintain the members 102 and 104 of the friction clutch normally in engagement, and the brake member 108 55 normally disengaged from the brake shoe. In order to disengage the clutch and engage the brake, the rod 106 is moved longitudinally to the left (Fig. 8). This movement of the rod compresses the coiled spring 122, 60 but does not affect the coiled spring 118 until the friction clutch is disengaged and the members of the brake are brought into engagement, since the spring 118 holds the blocks 110 against the shoulder 116, and the 65 brake member 108 moves with the rod 106.

Further longitudinal movement of the rod, however, after the brake is engaged, causes the compression of both the spring 118 and the spring 122, these springs then serving to engage the members of the brake with 70 considerable pressure. When the rod is released, the springs act together to carry it back in the opposite direction until the shoulder 116 on the rod engages the inner ends of the blocks 110, after which, by the 75 force of the spring 122, the brake member 108, rod and spring 118 are moved to the right together a slight distance, sufficient, however, to disengage the brake and engage the clutch. 80

The clutch member 86 is secured to and preferably formed integral with a sleeve 124 mounted loosely on the main shaft 46 of the machine, and extending from said clutch member toward the end of the shaft. The 85 clutch member 88 is secured to a flange 126 extending outwardly from a sleeve 128 loosely journaled on the sleeve 124. The sleeve 128 is free to move longitudinally of the sleeve 124 and of the shaft 46, but is 90 caused to rotate with the shaft by a connection with the pulley 44. In the construction illustrated, the sleeve is provided with a pair of spaced shoulders or abutments 130, which receive between them an arc-shaped 95 lug 132 on the pulley 44. The sleeve is normally held in position longitudinally of the shaft with the clutch members out of engagement by means of a coiled spring 134 surrounding a bolt 136 passing through a 100 hole in the pulley 44 and secured in the sleeve 128, said spring being seated in a recess in the pulley 44, and acting against the head of the bolt. 105

When the clutch members are engaged, 105 the member 86 at such time being rotated at slow speed in a forward direction, they first act as a friction brake to slow down the speed of the main shaft until the shaft and the parts rotating therewith are moving at 110 the same speed as the member 86. The member 86 then acts as a driving member through its engagement with the clutch member 88 to drive the shaft in a forward direction until the devices which finally 115 bring the shaft to rest are brought into engagement. The clutch members are engaged at a definite point in a rotation of the shaft, and the shaft is finally brought to rest at the end of a definite interval after 120 the clutch members are engaged. The mechanism for engaging the members 86 and 88 of the clutch comprise a timing cam consisting of a cam groove 138, formed in the sleeve 128 and engaged by a cam roll 140 125 carried by an arm 142 of a bell crank lever pivoted on a shaft 144. The other arm 146 of the bell crank is provided with a recess 148 adapted to receive a projection 150 at the upper end of a locking pin 152 which is 130

normally held out of engagement with the arm 146, so that during the normal operation of the machine, the bell crank lever is oscillated idly by the cam. The locking pin 152 is mounted to slide vertically in the forward end of a slide 154 mounted to slide horizontally in suitable guides in the frame, and yieldingly held in forward position by a coiled spring 156 interposed between a shoulder on the slide and the end of a screw 158 threaded into the frame, by which the tension of the spring may be adjusted. The slide is provided with an extension 160 projecting rearwardly therefrom through a suitable perforation in the portion of the frame in which the slide is mounted, and the forward movement of the slide in its guides is limited by a nut 162 threaded on the extension 160. By adjusting this nut, the slide may be adjusted to bring the locking pin into a position such that the projection 150 on the locking pin will register with the recess 148 at the proper time in the rotary movement of the main shaft. The locking pin is forced upwardly in the slide by a coiled spring (not shown) seated in a recess in the slide 154 and engaging the head of the locking pin, and the lower end of the pin is connected with the treadle rod 68 so that the pin is held down with the projection 150 out of engagement with the recess 148 while the treadle is depressed and the main driving clutch engaged to drive the main shaft of the machine.

When the projection 150 on the locking pin engages the recess 148 in the arm of the bell crank lever, the lever is no longer free to oscillate, since it is locked to the slide 154, and by the action of the face of the cam groove 138 on the roll 140 carried by the arm of said lever, the clutch member 88 will be forced over into engagement with the clutch member 86 when the roll engages a certain point in the cam groove, which occurs at a definite point in the rotation of the main shaft. After the clutch members have been engaged, the slide 154 will be moved rearwardly in its guides against the tension of the spring 156 by the action of the cam groove 138 on the bell crank lever, and the force with which the clutch members are engaged will depend upon the tension of the spring 156.

The treadle rod 68 is connected with an arm 164 pivoted on a stud 166 mounted in a block 168 secured to the lower end of the locking pin. A latch 170 is also pivoted on the stud 166, and is arranged to engage beneath a shoulder 172 on the slide 154 and hold the locking pin from upward movement until the treadle rod has been raised sufficiently to leave the locking pin free to move upward into secure locking engagement with the recess in the arm of the bell crank lever. The latch is disengaged from the shoulder by the movement of the arm 164, due to the lifting of the treadle rod. A lost motion connection is provided between the arm and the latch to allow the treadle rod to be raised before the latch is disengaged from the shoulder 172. In the construction illustrated, the connection between the arm and the latch consists of a pair of shoulders formed on the hub of the arm adapted to engage corresponding shoulders on the hub of the latch. These shoulders are arranged so that when the arm is moved in either direction there is a certain amount of lost motion of said arm before the latch is actuated by the arm. When the treadle is depressed, the arm 164 swings down until one of the shoulders on its hub engages the opposed shoulder on the hub of the latch, after which the continued downward movement of the treadle acts to draw the locking pin down against the tension of its actuating spring. During this movement of the locking pin the latch 170 slides down along the outer face of the shoulder 172 and finally snaps in beneath said shoulder. When the treadle is released, the treadle rod first moves upwardly, swinging the arm 164 upwardly therewith without affecting the locking pin until the shoulder on the hub of the arm 164 engages the opposed shoulder on the hub of the latch 170. The latch 170 is then swung outward from beneath the shoulder 172, leaving the locking pin free to be forced upward by its actuating spring.

Mechanism is provided for timing the engagement of the locking pin with the arm 146 of the bell crank lever, so that the locking pin will not move into engagement with said arm until the arm is in a position substantially such that the recess 148 registers with the projection on the locking pin. This insures a secure locking engagement between the locking pin and the arm. The block 168 extends upwardly along the end of the slide 154, and a second block 174 is pivoted to the block 168 on a stud 176. The block 174 is forced in a direction to bring the said block up against the end of the slide 154 by a spring 178 coiled about the stud 176 and engaging a pin 180 secured in the block 174. A third block 182 is pivoted on a stud 184 at the upper end of the block 174, and is normally held down against the upper end of the block 174 by a spring pressed pin 180^a, the pointed extremity of which engages a recess in said block. When the locking pin is drawn down by the depression of the treadle, the block 174 is swung outwardly away from the end of the slide 154 by the engagement of a shoulder 182^a on the forward end of the slide with a shoulder 184^a on the block 174. When the latch 170 is released from beneath the projection 172, and the locking pin is forced upward by its actu-

ating spring, the shoulder 184^a is disengaged from the shoulder 182^a, and the block 174 swings inwardly under the influence of the spring 178 and brings up against the end 5 of the slide. The block 174 is provided with a shoulder 186 which is adapted to engage beneath a shoulder 188 formed on the forward end of the slide 154, when the block 174 is swung inwardly into engagement with the slide. The engagement of the shoulder 186 with the shoulder 188 prevents the locking pin from being forced upwardly while they are engaged. The block 182 projects 10 above the upper face of the slide 154, and the arm 146 of the bell crank lever operates close to the upper face of the slide. When the arm 146, during the oscillatory movement of the bell crank lever, arrives in a position such that the recess 148 registers 15 with the projection 150, the lever strikes the inner face of the block 182 and knocks said block and the block 174 on which it is mounted, away from the end of the slide, thereby disengaging the shoulder 186 from beneath 20 the shoulder 188, and permitting the locking pin to be forced upwardly to engage the projection 150 in the recess 148.

When it is desired to stop the machine 30 without throwing the stop mechanism into operation, the block 182 may be swung about its pivotal connection with the block 174 by a manipulation of the arm 188^a formed on said block, the block then being held in position by the engagement of the pin 180 35 in a second recess in the block. When the block has been thus adjusted it will be out of the path of the arm 146 of the bell crank lever when the block 174 swings in against the end of the slide to bring the shoulder 186 40 beneath the shoulder 188. The engagement of these shoulders will prevent the locking pin from being forced upward into locking engagement with the arm 146 of the bell crank lever, and the machine is then allowed 45 to slow down gradually until it comes to rest.

The cam groove 138 is preferably timed 50 so that the arm 146 of the bell crank lever is moved into a position to bring the recess 148 into registration with the projection 150 just as the roll 140 arrives at an idle portion of the cam groove, thereby allowing the shaft to rotate a certain interval after the projection 55 150 is engaged in the recess 148, before the clutch members are engaged. This permits the projection 150 to become firmly seated in the recess 148 before the cam acts to engage the clutch members.

60 After the slow speed clutch members 86 and 88 are engaged and the shaft has been slowed down to the speed of the slow speed driving member 86, and while it is being driven at slow speed in a forward direction 65 by said member, the stopping devices which

finally bring the shaft to rest are brought into engagement. One of these devices is carried by one of the driven parts, and the shaft is disconnected from the driving mechanism and its rotation arrested by mechanism which is actuated by the movement of the positively driven stopping device. The clutch members 86 and 88 are still engaged when the main shaft is brought to rest, and the rotation of said shaft is arrested by disengaging the clutch which connects the hollow shaft 92 with the pulley 98 and engaging the brake member 108 with the brake shoe 114 to stop the rotation of said shaft and the pinion 90. The stopping devices 70 through the engagement of which the main shaft is finally brought to rest comprise a finger or shoulder 190 carried at the forward end of an arm 192 and adapted to be engaged by a projection or lug 194 secured to 75 or formed integral with the flange 126. The arm 192 is mounted for movement to carry the finger 190 into and out of the path of the lug 194, and to this end is secured to a rock shaft 196 journaled in an arm 198 80 which is pivoted on a shaft 200. When the locking pin is in lowered position with the projection 150 out of engagement with the recess 148, the arm 192 is held down so that the shoulder 190 is out of the path of the 85 projection 194 by a block 200^a secured to the lower end of the locking pin, which engages a roll 202 carried by an arm 204 secured on the rock shaft 196. When the locking pin is forced upward to engage the projection 100 150 in the recess 148, the arm 192 is swung upwardly to bring the shoulder 190 into the path of the lug 194 by a tension spring 206. The arm 198 which is pivoted on the shaft 200 extends downwardly in position to engage 105 the end of the rod 106. When the lug 194 engages the shoulder 190 on the arm 192, it carries the arm 192 to the left (Fig. 6), thereby swinging the arm 198 to the left about the shaft 200 and engaging the end of 110 the arm 198 with the end of the rod 106. The rod 106 is thereby thrust longitudinally against the tension of the spring 118 in a direction to disengage the clutch members 102 and 104, and to engage the brake member 108 with the brake shoe. After the brake is engaged further movement of the shaft 106 takes place against the tension of both the springs 118 and 122, thereby 115 forcing the brake members more firmly into 120 engagement. The springs 118 and 122 cushion the action of the stopping devices so that the parts are brought to rest without shock or jar and without excessive strain on any of the parts. When the forward rotation of 125 the shaft has been arrested, the parts are securely locked together, thereby preventing recoil.

It will be obvious that the lug 190 will engage the projection 194 at the end of a 130

definite interval after the members of the slow speed clutch are engaged, and the main shaft will be stopped at a definite point in its rotary movement. The cam groove 138 5 and the lug 194 are relatively arranged so that the interval between the engagement of the members of the slow speed clutch and the engagement of the stopping devices is sufficient to insure that the shaft will be 10 slowed down to the speed of the driving member of the slow speed clutch and will be driven thereby at slow speed before the stopping devices are engaged.

15 In order to prevent breakage of the parts
in case the stop mechanism fails to act prop-
erly and the shaft is not slowed down to the
speed of the driving member of the slow
speed clutch when the lug 190 engages the
projection 194, a projection 206 is formed
20 on the arm 192 and is provided with an in-
clined face 208. If the shaft and the parts
rotating therewith are moving at a higher
speed than the speed of rotation of the slow
speed driving clutch member when the lug
25 190 engages the projection 194, the arm 192
will be carried over farther to the left than
under normal conditions, and the inclined
face of the projection 206 will be brought
into engagement with an inclined face 210
30 on the frame, and the arm 192 will be thrown
down so as to disengage the projection 194
from the lug 190 and allow the shaft to
make another rotation before it comes to
rest.

35 In the illustrated embodiment of the invention, the parts are so timed that the members of the braking and slow speed forward driving clutch are engaged while the needle is retracting out of engagement with the
40 work, and the stopping devices are arranged to bring the shaft to rest when the needle is near the limit of its upward stroke, but also when the shaft is in a position such that the parts of the needle actuating mechanism
45 which act to vary the retracting stroke of the needle and the variable friction clamp of the presser foot lifting mechanism are unlocked, which occurs after the needle has completed its loop drawing stroke and has
50 just started to descend. This is the position of the parts most suitable to permit the removal and introduction of work, since the presser foot may be lifted freely by the actuation of the treadle. The descent of
55 the needle a slight distance from the limit of its retracting stroke before the machine is brought to rest is of advantage, since the needle loop is thereby slackened slightly and may be more easily severed. After the seam
60 has been completed and the machine brought to rest, the operator severs the leg of the needle loop which leads to the work. At that point in a cycle of operations at which the needle is retracted out of engagement
65 with the work and near the limit of its re-

gaged by a shoulder 250 on the arm 198. When, upon stopping the machine, the arm 198 is swung to the left (Fig. 6), through the engagement of the lug 194 with the projection 190, the shoulder 250 on said arm engages the end of the slide 248 and carries said slide to the left therewith. This movement of the slide 248 actuates the arm 246, shaft 244 and arm 242 in a direction to retract the slide 236, and to withdraw the head of the plunger 226 from the hole in the link 212. When the link 212 has been thus disconnected from the arm 214, the feed point is immediately drawn back into retracted position on the presser foot by a spring 252 which engages the end of the link 212.

When the machine is started, the arm 198 is thrown back by the springs 118 and 122, releasing the slide 248 and the mechanism connecting said slide with the plunger 226, and allowing the forward end of the plunger to be forced against the inner face of the link 212. When the movement of the arm 214 brings the head of the plunger into registration with the hole in the link 212, the head of the plunger snaps forward into the hole in the link, owing to the action of the spring 232. Upon starting the machine, therefore, the feed point is started into operation in timed relation to the other parts of the machine.

While it is preferred to employ the specific construction and arrangement of the parts shown and described, since this construction and arrangement is the simplest and most efficient embodiment of the invention which has yet been devised, it will be understood that this construction and arrangement is not essential except so far as specified in the claims, and may be varied or modified without departing from the broader features of the invention.

Having explained the nature and object of the invention, and specifically described one form of machine in which it may be embodied, what is claimed is:—

1. A sole sewing machine, having, in combination, stitch forming devices comprising a straight hook needle, a work supporting horn, a vertically and laterally movable feed point, mechanism for moving the feed point laterally to feed the work, means operated by the lateral movement of the feed point for moving the feed point into and out of engagement with the work, and means for supporting the feed point and for controlling the position thereof constructed and arranged to maintain the angular position of the feed point unvaried during its advancing movement in the direction of feed to feed the work.

2. A sole sewing machine, having, in combination, stitch forming devices comprising

a straight hook needle, a work supporting horn, a vertically and laterally movable feed point, mechanism for moving the feed point laterally to feed the work, cam acting means operated by the lateral movement of the feed point for moving the feed point into and out of engagement with the work, and means for supporting the feed point and for controlling the position thereof, constructed and arranged to maintain the angular position of the feed point unvaried during its advancing movement in the direction of feed to feed the work.

3. A sole sewing machine, having, in combination, stitch forming devices comprising a straight hook needle, a work supporting horn, a vertically and laterally movable feed point, mechanism for moving the feed point laterally to feed the work, means operated by the lateral movement of the feed point for moving the feed point into and out of engagement with the work comprising a cam fixed in the direction of feed, and means for supporting the feed point and for controlling the position thereof, constructed and arranged to maintain the angular position of the feed point unvaried during its advancing movement in the direction of feed to feed the work.

4. A sole sewing machine, having, in combination, stitch forming devices comprising a straight hook needle, a work supporting horn, work feeding mechanism comprising a slide, a block arranged for movement with the slide and to move independently thereof in a direction angular to the direction of movement of the slide, a feed point mounted on the block, faces formed on the slide and block for sliding engagement to maintain the angular position of the block and of the feed point unvaried during the advancing movement of the feed point in the direction of feed to feed the work, mechanism for moving the block horizontally in the line of feed to impart work feeding movements to the feed point, and means operated by the horizontal movements of the block for actuating the block to move the feed point into and to withdraw it from engagement with the work.

5. A sole sewing machine, having, in combination, stitch forming devices comprising a straight hook needle, a work supporting horn, work feeding mechanism comprising a horizontally and vertically movable slide, a feed point mounted thereon, a vertically movable slide having a sliding engagement with said first slide to maintain the angular position thereof unvaried during the advancing movement of the feed point to feed the work, a vertically movable bar for supporting said slides having a cam slot formed therein, a pin fixed in said first slide and engaging the cam slot in said bar, and mechanism for moving the first slide laterally of

the bar to impart work feeding movements to the feed point and thereby reciprocate the pin in the cam slot to move the feed point into and out of engagement with the work.

5 6. A sole sewing machine, having, in combination, stitch forming devices comprising a straight hook needle, a work supporting horn, a feed point, means for moving the feed point into and out of engagement with the work and for advancing and retracting it in the direction of feed, and means for moving the feed point from its normal position in a direction away from the needle upon stopping the machine to allow the 15 thread of the needle loop to be severed.

7. A sole sewing machine, having, in combination, stitch forming devices including a straight hook needle, a work supporting horn, a feed point, means for actuating the feed point, and means for moving the feed point from its normal position in a direction away from the needle to allow the thread of the needle loop to be severed upon stopping the machine with the needle out of the work.

25 8. A sole sewing machine, having, in combination, stitch forming devices including a straight hook needle, a work supporting horn, a feed point, means for moving the feed point into and out of engagement with the work and for advancing and retracting it in the direction of feed, and means for moving the feed point from its normal position in a direction away from the needle to allow the thread of the needle loop to be severed upon stopping the machine at a point 30 in a cycle of operations when the needle is out of the work and the feed point is somewhat advanced from its retracted position.

9. A sole sewing machine, having, in combination, stitch forming devices including a straight hook needle, a work supporting horn, a feed point, mechanism for actuating the feed point, and means acting automatically upon stopping the machine to move the 45 feed point away from its normal position in a direction away from the needle to allow the thread of the needle loop to be severed.

10. A sole sewing machine, having, in combination, stitch forming devices including a straight hook needle, a work supporting horn, a feed point, means for actuating the feed point, and means for disconnecting the feed point from its actuating mechanism and withdrawing it from its normal position 50 in a direction away from the needle to allow the thread of the needle loop to be severed upon stopping the machine.

11. A sole sewing machine, having, in combination, stitch forming devices including a straight hook needle, a work supporting horn, a feed point, mechanism for actuating the feed point, and means acting automatically upon stopping the machine to disconnect the feed point from its actuating

mechanism and withdraw it from its normal 65 position in a direction away from the needle to allow the thread of the needle loop to be severed.

12. A sole sewing machine, having, in combination, a main shaft, stitch forming devices including a straight hook needle, a work supporting horn, a feed point, means for actuating the feed point, a stop mechanism for arresting the rotation of the shaft, and means controlled by the stop mechanism 70 for automatically moving the feed point from its normal position in a direction away from the needle to allow the thread of the needle loop to be severed upon stopping the machine.

80 13. A sole sewing machine, having, in combination, a main shaft, stitch forming devices including a straight hook needle, a work supporting horn, a feed point, means for actuating the feed point, a stop mechanism for the shaft, and means controlled by the stop mechanism for automatically disconnecting the feed point from its actuating mechanism and withdrawing it from its normal position in a direction away from the 85 needle to allow the thread of the needle loop to be severed upon stopping the machine.

14. A sole sewing machine, having, in combination, a shaft, stitch forming devices including a straight hook needle, a work supporting horn, a feed point, means for actuating the feed point, a stop mechanism for the shaft comprising stopping devices for finally bringing the shaft to rest at a predetermined point in its rotary movement, 95 mechanism actuated by the engagement of the stopping devices for disconnecting the feed point from its actuating mechanism, and means for withdrawing the feed point from its normal position in a direction away from the needle to allow the needle loop to be severed when it has been disconnected 100 from its actuating mechanism.

15. A sole sewing machine, having, in combination, stitch forming devices comprising a straight hook needle, a work supporting horn, a feed point, mechanism for actuating the feed point, means for disconnecting the feed point from its actuating mechanism and withdrawing it from its normal position in a direction away from the needle to allow the needle loop to be severed upon stopping the machine, and means for automatically restoring the feed point to 110 connection with its actuating mechanism 115 upon starting the machine.

16. A sole sewing machine, having, in combination, stitch forming devices comprising a straight hook needle, a work supporting horn, a vertically and laterally movable feed point, a feed point carrier, means for advancing and retracting the carrier in the direction of feed, means for maintaining 125

- the carrier in an unvaried angular position during its advancing movement, and a pivotal connection about which the carrier is permitted to swing during the first part 5 of the movement of the carrier by which the feed point is retracted in the direction of feed:
17. A sole sewing machine having, in combination, stitch forming devices comprising, a straight hook needle, a work supporting horn, a vertically and laterally mov-

able feed point, a feed point carrier, means for advancing and retracting the carrier in direction of feed, means for maintaining the carrier in an unvaried angular position during its advancing movement and a connection permitting the feed point to be moved vertically to a slight degree out of stock penetrating position by the retracting movement of the carrier. 15

WILLIAM C. MEYER.
